UNITED STATES PATENT OFFICE.

JAMES W. BERRY, OF IOWA CITY, IOWA.

SIPHON FOR FLUSH-TANKS.

1,128,575.

Specification of Letters Patent. Patented Feb. 16, 1915.

Application filed February 2, 1914. Serial No. 816,078.

To all whom it may concern:

Be it known that I, JAMES W. BERRY, a citizen of the United States, residing at Iowa City, in the county of Johnson and 5 State of Iowa, have invented a new and useful Siphon for Flush-Tanks, of which the following is a specification.

The present invention appertains to a siphon for flush tanks, and aims to provide 10 an apparatus of the nature indicated, which is particularly adapted for sewage systems, and the like.

It is the object of the present invention to provide a siphon of simple, compact and inexpensive construction, and possessing the fewest number of component parts possible, which shall be adapted for application within a flush tank, for intermittent automatic operation as the tank is continually filled 20 with water or other fluid.

It is also the object of the present invention to provide a siphon of the nature indicated, which will be adapted for connection with a sewer or other conduit, for intermittently flushing the same.

A further object of the present invention is to provide a siphon for flush tanks, which will render unnecessary, the usual deep seal trap, disposed or embedded below the floor 30 or bottom of the tank, the present siphon being adapted to be disposed upon the floor or bottom of the tank for direct connection with the sewer or conduit without the intervention of a deep seal trap between the 35 sewer or conduit and the bottom or floor of the tank, whereby ready inspection of sewer is possible.

A still further object of the present invention is to provide an apparatus of the 40 character specified, embodying a relief trap, which will relieve the main trap of the pressure as the water level rises within the tank, in order that the main trap will be brought quickly into full action, when the water 45 level rises to a predetermined point, and whereby the rapid discharge of the water from the tank into the sewer or conduit will ensue.

With the foregoing general objects out-lined, and with other objects in view, which will be apparent as the nature of the invention is better understood, the present inven-

tion resides in the combination and arrangement of parts and in the details of construction hereinafter described and claimed, it 55 being understood that changes in the precise embodiment of the invention herein disclosed can be made within the scope of what is claimed without departing from the spirit of the invention.

The invention has been illustrated in its preferred embodiment in the accompanying drawings, wherein—

Figure 1 is a vertical central section of a flush tank illustrating the present improvements applied thereto, portions being broken away. Fig. 2 is a cross section of the siphon, taken on the line 2—2 of Fig. 1.

In the drawings, the numeral 1 designates the usual flush tank, which may be of any 70 suitable cross sectional area or outline, according to the volume of water which is to be discharged at each operation of the siphon. The tank 1, as is usual, is supplied with water by a supply pipe 2, which is normally open, when the apparatus is in operation, so that a continuous stream of water 75 flows into the tank 1.

In carrying out the present invention, an annular channel 3 is seated on the bottom of 80 the tank, the inner wall 4 of the channel having its lower end extended, as at 5, below the bottom of the channel, so as to pass through the bottom or floor of the tank 1, to communicate with the end or a branch 85 of a sewer 6, or other conduit to be flushed. The channel 3 is relatively deep and is preferably in the form of a casting, the central opening of the channel, formed by the inner wall 4 thereof, communicating through 90 the tank bottom and with the sewer or conduit 6, and also permitting ready access to be had to the sewer or conduit, for purpose of inspection or otherwise.

Within the bottom portion of the annular 95 channel 3, are a plurality of radial webs 7, which connect the inner and outer walls 4 and 8 of the channel, respectively, and which are also integral with the bottom of the channel, the upper edges of the webs being V-shaped, as seen in Fig. 1.

A bell or dome 9 is disposed over the channel 3, and a depending sleeve or annular petticoat 10 is carried by the head or top

of the bell 9 and enters the channel 3, so as to normally seat upon the webs 7. Thus, the sleeve or petticoat 10 seating on the webs 7 will normally support the bell 9, the 5 V-shaped upper edges of the webs tending to center the bell, or to place the same into concentric relation with the channel. The bell 9 is preferably provided with a sniff or vent aperture 9^a at one side and adjoining 10 its lower edge. The top or head of the bell is preferably provided with a hand hold 11 for convenience in lifting or removing the bell from the channel.

The sleeve 10 being disposed within the 15 channel 3, forms a main trap, the outer leg of which is defined between the outer wall or periphery 8 of the channel and the sleeve 10, and the inner leg is defined by the inner wall 4 of the channel and the sleeve 10. 20 In connection with this main trap, there is provided a relief trap 12, which is of U-shape, and is disposed within the central opening 4, one arm or limb of the relief trap 12 being extended upwardly through the top 25 or head of the bell and having the extension 13 passing back through the top or head of the bell outside of the sleeve 10 so as to communicate with the upper end of the outer limb of the main trap. That portion of the 30 outer limb of the relief trap 12 above the top or head of the bell 9 is provided with an upstanding branch 14 having a removable cap 15, whereby when the cap is removed, the relief trap 12 may be primed, as when the 35 device is first started to operate, or when the relief trap is emptied by evaporation. The other arm or limb of the relief trap is shorter in length than the inner arm or limb of the main trap, whereby the relief trap 40 will be discharged or opened, prior to the siphonic action through the main trap. As will be evident, the relief trap 12 will be carried by the bell.

In operation, the channel 3 is normally 45 filled with water, so as to fill the main trap, and the relief trap 12 is also filled with water. Now, as the water flows into the tank 1 from the supply pipe 2, the water level will rise within the tank, and as the water 50 level rises, the column of air between the periphery or apron of the bell 9 and the outer wall 8 of the channel or main trap will be brought under compression, thereby forcing the water within the outer limbs of the 55 main and relief traps downwardly or inwardly. Thus, the water will rise within the periphery or skirt of the bell, toward the upper edge or end of the outer wall 8 of the channel or main trap. Thus, as the 60 column of water between the periphery or apron of the bell and the outer wall of the channel or main trap reaches or approaches the end of the outer arm or limb of the main trap, the air being forced into the outer

limbs of the main and relief traps, the relief trap is discharged, prior to the main trap, so as to release the air above the outer limb of the main trap, through the relief trap, whereby the siphonic action through the main trap will be established in 65 the manner indicated. When the level of the water within the tank reaches a predetermined level, known as the "discharge line", the siphonic action through the main trap will be set up, whereby the water within the tank will be rapidly discharged into the sewer or conduit to flush the same. The water, during the siphonic action, flows upwardly within the periphery or rim of the bell 9, and thence through the main trap 70 and down through the opening formed by the inner wall 4 of the channel or main trap to the sewer or conduit, in the directions of the arrows in Fig. 1. After the tank has been emptied, due to the siphonic action, the 75 vacuum will be broken, when the water level reaches the lower end of the bell 9, thus permitting the air to enter the bell, and consequently, the water between the rim or periphery of the bell and the outer wall 8 80 of the channel, will flow back into the bottom of the tank 1, the sniff or vent aperture 9^a permitting the air to be admitted into the bell after the water level within the bottom tank rises above the lower edge or end of 85 the bell. The sniff aperture 9^a, however, will not seriously interfere with the siphonic action, inasmuch as the area of the aperture 9^a is comparatively small. After the bell 9 has been emptied, as intimated, the channel will remain filled with water, so as to 90 fill the main trap, which is also true of the relief trap, whereby it will be apparent that as the tank again becomes filled, the foregoing operation will be repeated. Thus, as 95 the tank is continually filled with water through the supply pipe 2, the siphon will be automatically operated at intermittent intervals, according to the rapidity at which the tank is filled. 100

The present siphon is comparatively 105 simple and does not embody any moving parts, it being observed that the customary deep seal trap below the floor or bottom of the tank, is not employed, which is desirable. Thus, by removing the bell, ready and direct access is had to the sewer or conduit, for purpose of inspection, or otherwise. The present device is particularly adapted 110 for use in sewage systems, and the like, 115 wherein the flush water is to be discharged rapidly and in a large volume. 120

Having thus described the invention, what is claimed as new is:

A tank siphon including an annular channel, the inner wall of which defines a central opening, a bell mounted over the channel and having a depending sleeve entering the 125

same, and a U-shaped relief trap disposed within the central opening and having one arm extended upwardly through the top of the bell and thence back through the top of the bell outside of the sleeve, that portion of the relief trap above the top of the bell having a removable closure.

In testimony that I claim the foregoing as my own, I have hereto affixed my signature in the presence of two witnesses.

JAMES W. BERRY.
